FOREIGN PATENT DOCUMENTS

KR 20110123641 1/2012

Primary Examiner — Marcus A Jackson(74) *Attorney, Agent, or Firm* — Sarah M. Walkington(57) **CLAIM**

The ornamental design for a portion of a flashlight, as shown and described.

DESCRIPTION

FIG. 1 is a perspective view of a portion of a flashlight showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings depict portions of the portion of a flashlight that form no part of the claimed design.

1 Claim, 6 Drawing Sheets(56)
